No. 11,547

DEC 23, 1879

UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET-BORDER.

Specification forming part of Design No. **11,547**, dated December 23, 1879; application filed November 24, 1879.
[Term of patent 3½ years.]

To all whom it may concern:

Be it known that I, THOMAS J. STEARNS, of Boston, in the county of Suffolk and State of Massachusetts, have invented a new and original Design for Carpet-Border, of which the following is a specification.

The nature of my design is fully shown in the accompanying photographic illustration.

The design consists chiefly of two ornamented bands or stripes, A B, extending lengthwise of the piece, the stripe A being at one edge, and the stripe B separated from the stripe A by about two-thirds of the width of the piece. The stripe A is ornamented by a row of angular figures, *a*, and the stripe B is ornamented by a series of Gothic figures, *b*, and lines *c*. Between the stripes A B are floral designs C C, and on the farther side of

the stripe B is a row of smaller floral designs D D.

I claim—

1. The design for a carpet-border, having the ornamented stripes A B, arranged as shown.

2. The design for a carpet-border, having the ornamented stripes A B and the floral designs, as shown.

In testimony whereof I have signed my name to this specification in the presence of two subscribing witnesses this 20th day of November, 1879.

THOMAS J. STEARNS.
